UNITED STATES PATENT OFFICE.

WILLIS H. WEST, OF TRINIDAD, COLORADO.

WINDOW-VENTILATOR.

1,209,366.

Specification of Letters Patent. Patented Dec. 19, 1916.

Application filed December 20, 1915. Serial No. 67,765.

To all whom it may concern:

Be it known that I, WILLIS H. WEST, a citizen of the United States, and a resident of Trinidad, in the county of Las Animas 5 and State of Colorado, have invented certain new and useful Improvements in Window-Ventilators, of which the following is a specification.

My invention relates to means for ventilating rooms and apartments of buildings without drafts, and the main object thereof is to provide such a device for use in a window frame of the conventional vertically 10 movable sash type and by means of which device the degree of ventilation may be in 15 complete control while preventing direct air currents upon an occupant of the room so ventilated.

A further object is to provide such a device in a compact form ready for instant installation within a window frame and as 20 readily detached therefrom, which will positively prevent the admission of rain or snow to the room, and which is comparatively 25 inexpensive.

My invention is fully described in the following specification, of which the accompanying drawings form a part, in which like characters refer to like parts in each of the 30 views, and in which:—

Figure 1 is a fragmentary perspective view of a window frame, from the interior of a building, provided with my invention in open position; Fig. 2 is a vertical section 35 taken on the line 3—3 of Fig. 1, with the ventilator in closed position; Fig. 3 is a section taken on the line 3—3 of Fig. 1; Fig. 4 is a side elevation of the ventilator detached 40 from the window; and Fig. 5 is a detached view of a detail.

In Figs. 1 to 3, inclusive, I have shown, fragmentarily, a window frame 5 provided with vertically movable sashes, only one of which, 6, is shown, this being the inner and 45 lower sash and is raised to permit the installation of my invention, as is clearly shown in said figures.

My ventilator comprises side plates 7 formed to fit the window frame and joined 50 by an inner vertical member 8 and a downwardly and outwardly inclined member 9 as well as by a relatively narrow strip 10 arranged horizontally at the upper and outer corners of the side plates 7, and I provide a 55 screen 11 at the outer side of the box-like structure so formed, this box, however, be-

ing open at its lower side and, with the exception of the strip 10, is also open at its top. The lower edges of the side plates 7 are cut to fit the window sill, and the upper inner 60 corners are cut away to form downwardly and inwardly inclined supports for a lid 12 hinged to the front member 8 and provided with dependent end members 13. These end members 13 are arranged within though in 65 close proximity to the side plates 7 to prevent the admission of the elements therebetween, and a knob 14 is provided whereby the lid 12 may be swung upon its hinges 15.

At 16 is shown a latch hinged to the under side of the lid 12 at 17 and provided with a plurality of teeth 18 along its upper edge for engagement with the under edge of the sash 6 when the latter has been moved downwardly to rest upon the upper edges of the 75 side plates 7 and, when the ventilator is properly placed and the sash so lowered, it will be noted that the strip 10 bears against the sash at its outer side and the lid 12 bears against said sash on its inner side, thereby 80 excluding wind, rain, snow, dust, etc., from the building equipped with my invention.

At 19 is shown a vertical rod passed through a slot 20 in the latch 16 to guide the latter when vertically moved to desired position with respect to the sash 6, and said rod carries a coil spring 21 bearing against the under side of the latch to insure engagement thereof with said sash. As shown at 22, I also provide a coil spring for maintaining the lid 12 in adjusted position and which spring 22 also aids in maintaining the latch 16 in desired position.

When the parts are in the positions shown in Fig. 2, the elements are excluded from the 95 room provided with my invention but, whenever desired, the lid 12 may be moved upwardly on its hinges until the desired tooth 18 engages the sash 6, and ventilation to that extent is assured, but no rain or snow may 100 enter the room because of the screen 11, and the strip 10 and the inclined member 9 against which any rain or snow passing said screen will impinge, and will be carried thereby downwardly and outwardly of the 105 ventilator.

My invention may be readily removed from the window by merely raising the sash 6 a few inches from its operative position shown, and the ventilator is, therefore, 110 adaptable to all climates and to all weather conditions.

5 The ventilator will be made to fit window frames of different widths, and may be made of any desired materials and of any desired finish as, for instance, to conform to the finish of the room provided with the ventilator, these features being arbitrary, as will be understood.

10 While I have shown a preferred form of structure, I do not limit myself thereto, but may make changes thereover provided that I do not depart from the spirit of the invention and remain within the scope of the appended claim.

15 Having fully described my invention, what I claim as new, and desire to secure by Letters Patent, is:—

A ventilator, comprising a casing open at its outer side and adapted to be inserted beneath a window sash to rest upon the win-

dow sill, the closed top of said casing having a slot therein to receive said sash in a weatherproof manner, a normally closed lid on the upper inner side of said casing and bearing, when closed, against said sash, and means for adjustably holding said lid in desired open positions, said lid consisting of a board hinged to the inner vertical member of the casing and having depending end members within the casing normally holding the lid in an inwardly and downwardly inclined position against the sash.

In testimony whereof I have signed my name to this specification in the presence of two subscribing witnesses.

WILLIS H. WEST.
